UNITED STATES PATENT OFFICE

JOSEPH FLEISCHMAN, OF KEW GARDENS, NEW YORK

HAT PROTECTOR

Application filed September 14, 1927. Serial No. 219,388.

My present invention is concerned with hat protectors for emergency use in rain storms, primarily.

It is among the objects of the invention to provide a protector of minimum cost which may be produced complete from one sheet by a single operation, without the need for separate steps of assembly, that would increase the expense of production.

10 Another object is to provide a protector of the above type, easy to handle and conveniently kept in stock in compact form, readily applied to hats of various dimensions, both men's hats and ladies' hats, without providing an unusual or freakish appearance when worn, and conveniently used as an effective advertising medium.

In one embodiment of the invention, the protector is formed by a single stamping 20 operation to approximately the shape of a hat, the material which simulates the surface appearance of the hat being folded or pleated to form the side wall and rim.

The body of the protector may be made of 25 thin glazed water resistant paper and the rim of the sheet is attached as by cementing or gluing to a ring of heavier material, such as cardboard, which lies on the rim of the hat, to which it may also be secured as by a clamp.

30 Referring now to the drawings,

Fig. 1 is a perspective view illustrating a protector applied for use upon a hat,

Fig. 2 is a sectional detail through the edge of the protector showing in dotted lines one 35 position of the clip and a fragment of the hat,

Fig. 3 is a fragmentary sectional view through the hat,

40 Fig. 4 is a perspective view illustrating a modification, and;

Fig. 5 is a transverse view illustrating the mode of nesting the protectors.

The embodiment of Figs. 1 to 3 shows illustratively a protector for a straw hat. The protector is formed from a single sheet of water-resistant paper, in an appropriate die, to afford a flat crown 20 and to pleat the excess material, to form the side pleats 21 and the turned out rim pleats 22. Preferably the 45 rim is made of width somewhat greater than

than of the largest hat rim. In the straw hat application shown, the blank is provided with surface embossments and of coloring to simulate straw and has a band 23 printed thereon in the appropriate place. This band may 55 constitute a circle generally concentric with the blank from which the protector is made so that in the formation of the protector, the band is formed in correct place, as shown. Preferably, the flat part 22 of the protector 60 to cover the rear of the rim, has a metal fastener thereon for gripping the rim. This fastener may comprise a single strip 24 of plastic metal clipped as at 25 to the rim, and normally bent over inward toward the crown. 65 In use, the bent over part is turned outward as shown in Fig. 2 in dotted lines, and clipped under the rim of the hat.

If the protector is made of thin glazed paper of light weight, in order to impart 70 more body thereto, I prefer to secure the lower face of the rim thereof to a reinforcing annular frame 27 of cardboard or other relatively stiff body material. The rim may be secured to the body by cementing, gluing or other appropriate fastening means, and its 75 inner edge 27', preferably determines an aperture larger than the crown of the hat, so as not unduly to stiffen the edge e, and thereby prevent adaptation to a large hat. 80

The protector is made of only one size and will adapt itself to hats of various sizes. Preferably, the body 21 is made slightly larger than the smallest hats, so that the crown in that case will fit loosely, while in the 85 application to larger crowns, the pleats 21 will yield slightly for snugly embracing the crown. The yield in that case will take place quite readily at the junction between the rim 22 and the crown 21 of the protector, so that there is no danger of destroying the protector or in applying the same to the hat. After the protector is applied, the clip 24 is, of course, merely turned over to grip the hat rim, as 90 shown.

In Fig. 4 is shown a slight modification of the embodiment of Figs. 1 to 3, in which instead of the frame 27 for the rim, I provide a reinforce, consisting of two or more turns of metal wire 30, extending within the rim, 95 100

which is preferably made of two sheets 31 and 32 cemented together about the enclosed wire. In that case, the bottom or cover sheet 32 is preferably made of paraffin paper, so that the assembly is effected by pressure and heat.

10 The crowns of the protectors are preferably formed with a slight taper, so that the protectors may be kept on the shelf, in nested stacks, as best shown in Fig. 5, without consuming much space.

15 The protectors, are well adapted to have advertisements printed within the crown as at 33 in Fig. 4, the cost being borne by the advertiser giving away the protectors gratuitously.

20 It will be understood that the embodiment of protector is itself readily adapted for use as a hat rather than as a hat protector, more especially in rainy weather or at beaches.

25 The protector of the various types, may be kept in stock at news-stands, railway stations, drug stores, hotel and theatre lobbies, etc., for sale or gratuitous distribution to the public in case of an unexpected rain storm.

30 By reason of the extreme cheapness of the various types of protectors disclosed, it is feasible to discard the same after but a single use.

35 It will thus be seen that there is herein described an article in which the several features of this invention are embodied, and which article in its action attains the various objects of the invention and is well suited to meet the requirements of practical use.

40 As many changes could be made in the above construction, and many apparently widely different embodiments of this invention could be made without departing from the scope thereof, it is intended that all matter contained in the above description or shown in the accompanying drawings, shall be interpreted as illustrative and not in a limiting sense.

45 Having thus described my invention, what I claim as new and desire to secure by Letters Patent of the United States is:—

50 1. A hat protector comprising a unitary blank of thin glazed paper pleated to the form of a hat to be protected thereby and a reinforcing ring to which the lower face of the rim of said blank is affixed.

55 2. A hat protector comprising a unitary blank of water resistant paper conformed to the shape of the hat to be protected, said protector having a rim composed of two sheets and having a spiral reinforcing wire adhesively retained between said sheets.

60 Signed at New York city in the county of New York and State of New York this 13th day of September, A. D. 1927.

JOSEPH FLEISCHMAN.
